STOCKING

Herbert M. Suess, Elkins Park, Pa.

Application April 6, 1949, Serial No. 1,822

Term of patent 14 years

(Cl. D47—7)

To all whom it may concern:

Be it known that I, Herbert M. Suess, a citizen of the United States, residing in Elkins Park, in the county of Montgomery and State of Pennsylvania, have invented a new, original, and ornamental Design for a Stocking, of which the following is a specification, reference being had to the accompanying drawings, forming part thereof.

In the drawings:

Fig. 1 is a perspective view; Fig. 2 is a side elevation; Fig. 3 is a rear elevation of a stocking showing my new design; and Fig. 4 is a side elevational view on a small scale of a complete stocking embodying my new design.

I claim:

The ornamental design for a stocking, as shown.

HERBERT M. SUESS.
